souri

Application February 15, 1941, Serial No. 99,020

Term of patent 14 years

To all whom it may concern:

Be it known that we, Sterling H. Campbell and Frank H. Pietzsch, citizens of the United States of America, residing at the city of St. Louis, State of Missouri, have invented a new, original, and ornamental Design for Angle Cock Holder, of which the following is a specification, reference being had to the accompanying drawing, forming a part thereof.

In the drawing, Figure 1 is a front view of an

angle cock holder showing our new design; Figure 2 is a side view; Figure 3 is a rear view; and Figure 4 is a section taken on the line 4—4 of Figure 3.

We claim:

The ornamental design for an angle cock holder, as shown.
